UNITED STATES PATENT OFFICE.

ADELBERT E. HALL, OF BAY CITY WEST, MICHIGAN.

VALVE-GEAR.

1,078,277.

Specification of Letters Patent. Patented Nov. 11, 1913.

Application filed January 27, 1911. Serial No. 605,043.

To all whom it may concern:

Be it known that I, ADELBERT E. HALL, a citizen of the United States, residing at Bay City West, in the county of Bay and 5 State of Michigan, have invented a new and useful Valve-Gear, of which the following is a specification.

The present invention relates to improvements in valve gears for engines, and more 10 particularly for that class of gears used upon locomotives, the primary object of the present invention being the provision of a novel means for regulating the throw of the valve so that the desired speed and power 15 may be imparted to the pistons and drive wheels, the parts being so located as to not be affected by the movable portion of the boiler due to the inequalities in the road and surface conditions.

20 With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

25 In the drawings Figure 1 is a side elevation of the valve gear as applied to a locomotive. Fig. 2 is a top plan view of the same, showing it applied to both of the 30 valves. Figs. 3 and 4 are detail views of the slotted end and mounting of the link lever with the adjacent parts of the gear. Fig. 5 is an enlarged detail view of the interlocking shafts carrying the upstanding 35 arms, looking in the direction of the arrow Fig. 2.

40 Referring to the drawings, the numeral 1 designates the cross head of the power piston of the locomotive and which is slidably mounted in the usual frame 2 which has upstanding from the rear end, the standard or frame 3 which extends from one frame 2 at one side of the locomotive at a point below the boiler to the frame 2 at the opposite side. The respective valves 4 which are of usual construction, are operated through the rods 5, and in a manner as will presently appear.

45 Connected to the horizontal portion of the frame 3 one upon each side thereof, are the two brackets 6, each one of which

is provided with the curved rearwardly extending lug 6'. Connected to the rear face and centrally of the horizontal portion of the frame 3 is a journaling lug 8, which has 60 pivotally connected thereto, intermediate of its ends for horizontal swinging movement, the double lever or walking beam 9 which is manually controlled through a rod 10 extended to the cab (not shown) of the locomotive. Thus through the rod 10, the said double lever 9 may be oscillated as desired and maintained in the selected position.

65 Disposed for oscillatory movement within the journaling end 6^a of the bracket 6 is a stud or pin 11' which is carried by the elongated plate 11, said plate 11 being connected to its pin 11' forming the axis for the lever link 12 which as shown in Figs. 3 and 4 is maintained in its relative swinging 70 position by the arm 6 and the connection of the plate 11 to the upper end centrally of the arc-shaped slot 13 thereof. The lug or ear 14 which is carried by the cross head 1 is operably connected to the lower end of 75 the lever link 12 through the medium of the short link 15, so that the lever link 12 is oscillated, with the stud 11' its axis, by the cross head 1.

80 Slidably mounted for movement within 85 the arc-shaped slot 13 so as to regulate the throw of the respective valves 4, as will later appear, is a block 16, provided with a stud 17 which is pivotally mounted within the apertured enlargement 19 of the rod 18 or link 18, the forward end 18' of this rod being pivotally connected to the lower end of the link 20, while the upper end of the link 20 is pivotally connected to the forward curved end of the bell-crank lever 7 which 90 is pivoted at 7' to the extension arm 6' of its respective bracket 6.

95 The respective ends of the double lever or walking beam 9 are connected by means of the ball and socket joints or other pivotal connections to the lower ends of the short arms 7^a of the bell-crank levers 7. By 100 this construction, the movement of the walking beam or double lever 9 to the opposite position to that shown in Fig. 2, will cause 105 the curved end of the bell-crank lever 7 upon the right hand side of the locomotive to be elevated so that the block 16 will be moved upwardly within the arc-shaped slot 13 to a point nearer the stud 11', and as 110 the arm 7^a of the bell-crank lever 7 upon the left hand side of the locomotive is dis-

posed in an opposite inclined position to the arm 7^a at the right hand side, the bell-crank lever 7 controlled thereby will operate the block 16 at the left hand side to be elevated within the arc-shaped slot 13 of its respective lever link 12, thus the manipulation through the rod 10 of the walking beam 9 will simultaneously actuate both of the respective bell-crank levers 7 and thus simultaneously adjust the block 16 within the arc-shaped slot 13 of both of the lever links 12.

Carried upon opposite sides from the frame of the locomotive, to the rear of the respective frames 2 thereof, are brackets 21, in which are mounted for oscillation, the respective reduced pintles or stub shafts 22 of the valve controlling transversely disposed and interlocking bars or shafts 23—23', the detail structure of which is clearly shown in Fig. 5. These bars 23—23', as therein shown, are constructed identically and are each provided with the sleeve 23^a through which pass the respective stub-shafts 22 so that economy in space, in mounting the respective bars 23—23', is accomplished. Each one of these respective bars carry two upstanding arms 24—25, one at each end thereof, and as assembled, the arm 24 of the bar 23 is adjacent to and upon the same side of the locomotive as the arm 25 of the bar 23'.

The rear end of the two rods 18 are pivotally connected to the two upstanding arms 24, thus permitting the lever links 12 to oscillate the rods 18 and through the arms 24 simultaneously oscillate the respective bars 23—23', each of which in turn oscillates its respective arm 25, which has pivotally connected to its upper end, the rod or link 27 which is extended forwardly and along side of the rod 18. The forward ends of the respective rods or links 27 are pivotally connected by a pin 27' intermediate of the ends thereof and within the link 26, said link 26 being swingingly mounted upon the stud 26' carried by the plate 11, all as clearly shown in Figs. 3 and 4. A pin 28' pivotally connects the inner end of the rod 28 to the lower end of the link 26, and as the other end of the link 28 is pivotally connected to the rod 5 of the valve 4, it is evident that the reciprocation of the respective arms 25 will impart the desired reciprocation to the respective valves 4.

From the foregoing description, taken in connection with the drawings the operation of the present valve gear is readily understood, but briefly stated it is as follows: Assuming the parts to be in the position as shown in Fig. 1, and it is desired to limit or shorten the throw of the valve 4 at the left as viewed in Fig. 2, the rod 10 is moved to push upon the walking beam 9

so that the arm 7^a at the right Fig. 2, is moved forwardly to elevate the curved end of the bell-crank lever 7, this action through the link 20 lifting the forward end of the rod 18 and consequently sliding the block 16 upwardly within the arc-shaped slot 13 and thus decreasing the leverage or movement of the block 16 within the slot 13, so that the reciprocatory movement imparted to the lever link 12 will be imparted to the rod 18, but such reciprocation or stroke will be shorter than if the parts were in the position as shown in Fig. 1. This movement of the rod 18 will rock the arm 24 upon the right hand side of the locomotive and through the bar 23 operate the arm 25 upon the left hand side of the locomotive which through the links 27, 26 and 28, at the left hand side, will throw or move the valve 4 at the left of the locomotive as desired. At the same time the valve 4 at the right hand side of the locomotive as viewed in Figs. 1 and 2 will be similarly actuated through the bell-crank lever 7 and its adjacent parts at the left of the locomotive.

What is claimed is:

1. The combination with an engine frame, the pistons, the cross heads and the cylinders, of a valve gear, including a pair of brackets one to each cylinder, a lever pivoted to each bracket and having its lower end operably connected to its respective cross head, a bell-crank lever pivoted to each bracket, a rod operably connected to the bell-crank lever, coacting means carried by said rod and one end of the bell-crank lever whereby the range of movement of the rod may be varied and whereby said rod is operably connected for operation from the first lever, and a valve operably connected to said rod, the throw of said valve being controlled by the position of the rod relatively to the first lever.

2. The combination with an engine frame, the pistons, the cross heads and the cylinders, of a valve for each cylinder, a bracket carried by the frame, one to each valve, a lever provided with a slotted upper end having its lower end operably connected to its respective cross head, two bell-crank levers, one pivoted to each bracket intermediate of its ends, a rod operably connected to one end of each of the bell-crank levers and slidably connected intermediate of its ends to the slotted end of the first lever, a pair of bars journaled transversely of the engine frame, an arm carried at one end of each bar and operably connected to its respective rod, another arm carried at the opposite end of each of the said bars, and means for operably connecting the last mentioned arms to the valve.

3. The combination of an engine frame, the pistons, the cross heads and the cylinders, of a valve for each cylinder, a bracket carried

by the frame, one to each valve, a bell-crank lever mounted in each bracket, a lever link having its lower end operably connected to its respective cross head, the upper end of 5 said lever being pivotally connected to its respective bracket for reciprocatory movement, the upper end of said lever being provided with an arc-shaped slot therethrough, a block slidably mounted in said slot, a rod 10 connected to said block and having one end operably connected to its respective bell-crank lever, a bar journaled transversely of the frame, said bar being provided with an upstanding arm and one end operably connected to its respective last mentioned rod, a second arm carried by the bar at its opposite end, and means for operably connecting the last arm to the valve.

4. The combination with an engine frame, 20 the pistons, the cross heads and the cylinders, of a valve for each cylinder, a bracket carried by the frame, one to each valve, a bell-crank lever mounted in each bracket, a lever link having its lower end operably connected 25 to its respective cross head, the upper end of said lever being pivotally connected to its respective bracket for reciprocatory movement, the upper end of said lever being provided with an arc-shaped slot therethrough, 30 a block slidably mounted in said slot, a rod connected to said block and having one end operably connected to its respective bell-crank lever, a bar journaled transversely of the frame, said bar being provided with an upstanding arm at one end operably connected 35 to the last mentioned rod, a second arm carried by the bar at its opposite end, a link pivotally connected to the lever link near the upper end thereof, a rod connecting 40 the upper end of the last mentioned arm of the bar with said last mentioned link, and another rod connecting the link to the valve.

5. A valve gear, including a frame, a reciprocatory cross head, mounted in the frame, a reciprocatory valve, a bracket carried by the frame, a lever having a slot in its upper end connected at such slotted end to the bracket for swinging movement and 45 having its lower end operably connected to the cross head, a block slidably mounted in the slotted end of the lever, a rod connected intermediate of its ends to said block, a bell-crank lever connected to the bracket and 50 having one end operably connected to one end of the rod, manually operated means for actuating the bell-crank lever to slide the block within the slot of the slotted lever, and means for operably connecting said rod 55 to the valve to control the throw of the valve.

6. A valve gear, including a frame, a

reciprocatory cross head mounted in the frame, a reciprocatory valve, a bracket carried by the frame, a lever having a slot in its upper end connected at such slotted end to the bracket for swinging movement and having its lower end operably connected to the cross head, a block slidably mounted in the slotted end of the lever, a rod connected 65 intermediate of its ends to said block, a bell-crank lever connected to the bracket and having one end operably connected to one end of the rod, manually operated means for actuating the bell-crank lever to slide the 70 block within the slot of the slotted lever, a bar journaled transversely of the frame, an arm mounted upon each end of said bar, one of said arms being operably connected to the remaining end of the rod, a short link piv- 75 otally connected to the upper end of the slotted lever for independent movement thereof, and two rods pivotally connected to said link and extending in opposite directions, one of said rods being operably connected 80 to the remaining arm of the bar, while the other arm is operably connected to the valve.

7. A valve gear, including a frame, a reciprocatory cross head mounted in the frame, a reciprocatory valve, a bracket carried by the frame, a lever having a slot in its upper end connected at such slotted end to the bracket for swinging movement and having its lower end operably connected to the cross head, a block slidably mounted in the slotted end of the lever, a rod connected intermediate of its ends to said block, a bell-crank lever connected to the bracket and having one end operably connected to one end of the rod, manually operated means for actuating the bell-crank lever to slide the block within the slot of the slotted lever, a bar journaled transversely of the frame, an arm mounted upon each end of said bar, one of said arms being operably connected to the remaining end of the rod, a short link piv- 90 otally connected to the upper end of the slotted lever for independent movement thereof, and two rods pivotally connected to said link and extending in opposite directions, one of said rods being operably connected to the remaining arm of the bar, while the other arm is operably connected to the valve.

In testimony that I claim the foregoing as my own, I have hereto affixed my signature in the presence of two witnesses.

ADELBERT E. HALL.
